(57) **CLAIM**

The ornamental design for a scooter bag, as shown and described.

DESCRIPTION

FIG. 1 is a perspective view of the scooter bag of the present invention in its extended configuration;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front view of the scooter bag of the present invention in its collapsed configuration;

FIG. 9 is a back view thereof;

FIG. 10 is a right side view thereof;

FIG. 11 is a left side view thereof;

FIG. 12 is a top view thereof; and,

FIG. 13 is a bottom view thereof.

FIGS. 8 through 13 in the drawings are shown on an enlarged scale.
